US0D1057035S

(12) **United States Design Patent** (10) **Patent No.:** **US D1,057,035 S**
 Tetnowski (45) **Date of Patent:** **** Jan. 7, 2025**

(54) **FOLDABLE GEOMETRIC BLOCK**

(71) Applicant: **The Board of Regents of the University of Oklahoma**, Norman, OK (US)

(72) Inventor: **Jennifer Thompson Tetnowski**, Oklahoma City, OK (US)

(73) Assignee: **The Board of Regents of the University of Oklahoma**, Norman, OK (US)

(**) Term: **15 Years**

(21) Appl. No.: **29/894,956**

(22) Filed: **Jun. 15, 2023**
